Howden & Howden

UNITED STATES PATENT OFFICE

WILLIAM I. BOWDEN, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

FURNACE SIDE WALL

Application filed August 8, 1929. Serial No. 334,247.

This invention relates to improvements in the construction of furnace side walls, and more particularly to improvements in side walls of a type including fluid-cooled areas, 5 such for example as that illustrated in the copending United States application Serial Number 219,706, filed September 15, 1927.

One of the objects of the invention is to provide means for preventing molten slag 10 flowing down the side walls from coming into contact with the fluid-cooled areas and forming thereon a hardened coating preventing efficient operation of the fluid-cooled areas for their intended purposes.

15 The invention also has application to furnaces of the type including stokers having inclined retorts, and one of the objects of the invention is to provide means for preventing molten slag from running down the 20 furnace side walls to an extent and in a manner interfering with the normal movement of fuel in the immediately adjacent retorts.

In the attached drawing:

25 Figure 1 is a more or less diagrammatic vertical-sectional view through a stoker-equipped furnace illustrating an embodiment of my invention:

Fig. 2 is a section on the line 2—2, Fig. 1, 30 and

Fig. 3 is a sectional view similar to that of Fig. 2 illustrating a modification within the scope of the invention.

With reference to the drawing, 1 indicates 35 the front wall of a furnace having an opening 2 in which is established the forward end of a multiple-retort automatic stoker 3. The stoker extends from said opening into the furnace, the rear end thereof being supported upon a beam 4 at a point spaced apart from the rear wall 5 of the furnace to thereby form in the intervening space an ash pocket 6. The usual mechanism 7 is provided as a part of the stoker to advance 40 the fuel at predetermined rates down the inclined retorts.

The side walls 8 of the furnace are provided in the present instance with a fluid-cooled area 9 which may be made in accordance 50 with the principles set forth in the

aforesaid copending United States application Serial Number 219,706. As shown in Figs. 2 and 3, this fluid-cooled section may consist of a set of refractory blocks 10 assembled to form a section of the wall extending from the front wall of the furnace to the rear wall 5 and conforming approximately to the inclination of the inclined grate surface of the stoker. Associated with the refractory blocks 10 is a series of pipes 11 which connect with headers 12 and 13 located respectively behind the walls 1 and 5. These headers may be connected either with the circulating water system of the furnace or with an independent circulating fluid system whereby heat is continuously withdrawn from the blocks 10. The fluid-cooled panel 9 is so placed as to constitute an abutting surface for the burning fuel in the contiguous retorts.

In a furnace of this type and where a relatively narrow band of fluid-cooled side wall is employed, the refractory walls above the fluid-cooled sections are frequently sufficiently hot to permit molten particles of ash and eroded refractory material to flow down the walls, and when this molten slag comes in contact with the fluid-cooled panels, portions of the slag are chilled and hardened, thereby forming a coating of slag over the blocks 10 which increases in thickness as the operation of the furnace is continued until it becomes a serious factor in preventing efficient heat transfer through the fluid-cooled sections of the wall. I have

discovered that these undesirable accumulations of slag may be largely avoided by placing one or more tubes 14 above the fluid-cooled wall section, these tubes being placed at the inside of the wall and preferably in direct contact therewith and extending the full width of the wall between the front and rear walls 1 and 5, as illustrated. Preferably, the tube or tubes 14 are connected with the headers 12 and 13, as illustrated in Fig. 1, and thereby form a part of the circulating fluid system including the said headers and the pipes 11. The slag flowing down the side walls collects above the tube or thereon and drips off the inner edge of the tube

directly onto the fuel bed without coming into contact with the fluid-cooled wall section 9. Accumulations of hardened slag on the fluid-cooled surfaces are thereby effectively prevented.

- In the operation of stoker furnaces of the type illustrated herein, it has been found that the molten slag running down the side walls as previously described tends to 10 form obstructions seriously interfering with the advance movements of the fuel in the retorts. The slag flowing down the side walls in a continuous stream or sheet runs into the fuel bed, and as it reaches the cooler 15 temperature of the igniting fuel hardens and forms the fuel-retarding obstructions. The foregoing device constituted by the pipe or pipes 14 is effective to prevent the formation of these obstructions.
- 20 As described, the slag collects above and on the tubes 14 and drips from the inner edge of the latter onto the fuel bed in relatively small particles which are readily advanced in the retorts with the fuel itself.
- 25 The tubes 14 break up the continuous flow of slag and prevent the relatively large and solid accumulations, which as set forth above tend to obstruct the fuel movement.

While the use of pipes connected with a 30 fluid-circulating system has been found most effective for the purposes set forth and is therefore preferred, it will be apparent that some of the advantages of the invention may be realized by the employment of any similar 35 structural arrangement which prevents the continuous flow of molten slag down the side wall over the fluid-cooled sections of the latter (where the side wall includes such fluid-cooled section) and into the fuel bed.

40 I claim:

1. In a furnace, a stoker including a retort immediately adjacent a wall of said furnace and means for advancing fuel along the retort, means in said side wall above the top of 45 said retort for diverting molten slag flowing down said wall from the lower wall areas and for deflecting said slag into the fuel bed at points apart from the said wall, and a fluid-cooled panel in said wall below said deflecting means.

50 2. A furnace side wall comprising a fluid-cooled panel constituting an abutment for the fuel bed, and means on said side wall above the said panel for diverting molten slag flowing down the wall from the fluid-cooled panel and for deflecting said molten slag onto the fuel bed at points spaced apart from the said side wall.

- 55 3. In a furnace, a stoker including a retort adjacent a wall of said furnace, and means for advancing fuel along the retort, a shoulder extending along said wall above the top of said retort for diverting molten slag flowing down said wall from the lower 60 wall areas and for deflecting said slag di-

rectly into the fuel-bed at points apart from said wall, and a fluid-cooled panel in said wall below said shoulder.

4. In a furnace, a stoker including a retort adjacent a wall of said furnace, and means for advancing fuel along the retort, a fluid-cooled pipe extending along and in contact with said wall above the top of said retort for diverting molten slag flowing down said wall from the lower wall areas and for deflecting said slag directly into the fuel-bed at points apart from said wall, and a fluid-cooled panel in said wall intermediate said pipe and the top of said retort and constituting the said lower wall area.

5. In a device of the class described, a furnace wall, an inclined cooling panel provided in said wall, the inner surface of said panel being substantially flush with the inner side of the wall proper, and means provided on said wall above said cooling panel and projecting from the common plane of said wall and panel for diverting the flow of slag down the wall from the panel.

6. In a device of the type described, a furnace wall, a cooling panel provided therein, and slag diverting means comprising one or more fluid conducting tubes positioned above said wall panel, said tubes being arranged in offset relation with respect to said fluid cooling panel.

7. In a device of the class described, the combination with a furnace wall, fluid conducting tubes provided in said wall for cooling a portion thereof, slag diverting means comprising one or more fluid carrying tubes arranged in parallel offset relation with respect to said first mentioned tubes, said parts being so constructed and arranged that the molten slag flowing down said wall will be diverted away from the wall, leaving said first mentioned tubes free from slag.

8. In a device of the class described, the combination with a furnace wall, a panel provided therein having a series of fluid conducting tubes, a refractory placed on said tubes, the surfaces thereof exposed to the furnace being substantially flush with the wall proper, and slag diverting means comprising one or more water tubes arranged in parallel offset relation with respect to said panel, said parts being so constructed and arranged that the molten slag flowing down the wall will be diverted away from the wall, thereby leaving the surface of the panel free from slag.

9. In a furnace, a stoker including a grate and means for advancing fuel over said grate, a wall adjoining a side of said grate, means for cooling an area of said wall adjacent the top of the grate, and means projecting from the surface of said wall for diverting molten slag flowing down the wall from said area.

10. In a furnace, a stoker including a

grate and means for advancing fuel over said grate, a wall adjoining a side of said grate, tubes for conducting a cooling medium in association with said wall to provide a cooled wall area adjacent the top of the grate, and means projecting from the surface of said wall for diverting molten slag flowing down the wall from said area.

11. In a device of the type described, a

10

furnace wall, liquid cooling means for an area of said wall, and means comprising one or more fluid conducting tubes positioned above the bottom of said cooled area and projecting outwardly beyond the surface of the latter for diverting molten slag flowing down the wall from the lower portion of said area.
